CLAIM

The ornamental design for an adjustable clamping nut,
as shown and described.

DESCRIPTION

FIG. 1 is a perspective view of an adjustable clamping
nut showing my new design;

FIG. 2 is a right side elevational view thereof, the side
opposite being a mirror image thereof;

FIG. 3 is a rear elevational view thereof;

FIG. 4 is a reduced right side elevational view thereof,
the broken line showing of the bolt and the layers of
panels being shown in broken lines for illustrative pur-
poses only;

FIG. 5 is a reduced right side elevational view similar to
FIG. 4 with the adjustable nut clamp in an alternate
position.

FIG. 1

FIG. 2

FIG. 3

FIG. 4
